(57)

CLAIM

The ornamental design for a back shaver, as shown and described.

DESCRIPTION

FIG. 1 is a front view of a back shaver showing my new design;

FIG. 2 is a back view thereof;

FIG. 3 is a left side view thereof;

FIG. 4 is a right side view thereof;

FIG. 5 is a top view thereof; and,

FIG. 6 is a bottom view thereof.

The broken lines shown in the drawings depict portions of the back shaver that form no part of the claimed design.

1 Claim, 6 Drawing Sheets
